ATTORNEY

UNITED STATES PATENT OFFICE.

LOIS McG. WILLIAMS, OF FORT THOMAS, KENTUCKY, ASSIGNOR TO THE WADSWORTH WATCH CASE COMPANY, OF DAYTON, KENTUCKY, A CORPORATION OF KENTUCKY.

DESIGN FOR A WATCHCASE CROWN.

Application filed May 15, 1922. Serial No. 2,243. Term of patent 14 years.

To all whom it may concern:

Be it known that I, Lois McG. WILLIAMS, a citizen of the United States, residing at Fort Thomas, in the county of Campbell and State of Kentucky, have invented a new, original, and ornamental Design for Watchcase Crowns, of which the following is a specification, reference being had to the accompanying drawing, forming part hereof.

In the drawing:

Fig. 1 is a front elevation of a watch-case crown embodying my design, its relation to the other watch-case parts being indi-

cated by a conventional showing of the latter by dotted lines;

Fig. 2 is a side elevation thereof; and

Fig. 3 is a front elevation of the crown on an enlarged scale.

I claim:

The ornamental design for a watchcase crown, substantially as shown.

LOIS McG. WILLIAMS.
